UNITED STATES PATENT OFFICE.

ADONIRAM J. WILSON, OF PORT CHESTER, NEW YORK.

ELECTRIC SIGNALING SYSTEM.

SPECIFICATION forming part of Letters Patent No. 596,226, dated December 28, 1897.

Application filed December 21, 1895. Serial No. 572,902. (No model.)

To all whom it may concern:

Be it known that I, ADONIRAM J. WILSON, a citizen of the United States, and a resident of Port Chester, in the county of Westchester and State of New York, have invented a new and useful Improvement in Electric Signaling Systems, of which the following is a specification.

This invention relates to electrical signaling systems for railways, and has for its object to provide for the safe and rapid conduct of traffic by means of a simple and efficient system in which home and distant signals may be employed.

15 The invention consists of the construction and arrangement hereinafter pointed out.

In the drawing forming part of this specification one embodiment of the invention is clearly shown in diagram.

20 Referring now particularly to this illustrated embodiment of the invention, the track is divided into subsections 1, 2, 3, 4, 5, 6, 7, 8, and 9. The rails of these several subsections, as herein shown, are included in separate normally-closed track-circuits, which also include the magnets *a*, *b*, *c*, *d*, *e*, *f*, and *g*, subsections 3, 4, 6, and 7, also including circuit-controllers *b'*, *c'*, *e'*, and *f'*, operated by the magnets *b*, *c*, *e*, and *f*, respectively. The

30 track is divided into blocks, each including a plurality of subsections. Subsection 1 is the last subsection of block *W*. Subsections 2, 3, and 4 constitute the block *X*. Subsections 5, 6, 7, and 8 constitute the block *Y* next

35 in advance, and subsections 9, &c., constitute the block *Z* next in advance. The home signals *A*, *B*, and *C* guard the blocks *X* *Y* *Z* and are located at the entrance of their respective blocks. Near the home signals and

40 preferably on the same post are the distant signals *A'* *B'* *C'*, which guard the blocks next in advance of them—as, for example, distant signal *A'* guards block *Y*, distant signal *B'* guards block *Z*, and distant signal *C'* guards

45 the block next in advance of block *Z*. These signals are all normally at "danger," and each signal is operated or controlled by a normally-deenergized signal-circuit. The power for actually moving the signals may of course

50 be electric, pneumatic, mechanical, or other suitable power. Electric power, however, is preferred.

D, *D'*, and *D*² are the batteries for the signal-circuits.

The signal-circuits of the block *Y* will be 55 first explained. The signals for this block *Y* are the home signal *B*, located at the entrance of the block, and the distant signal *A'*, located in the rear of this signal, or, as shown, at the entrance of the block *X*. The circuit for the 60 signal *B* includes battery *D*², normally-closed circuit-controller *h*², wire 10, signal instrument or motor of signal *B*, magnet *n'*, normally open circuit-controller *m'*, and wire 20. The circuit for the distant signal *A'* includes 65 battery *D*², circuit-controller *h*², wire 10, wire 11, connected with wire 10 at 12, normally-closed circuit-controller *k*', wire 13, instrument or motor of signal *A'*, normally open circuit-controller *o*, and wires 14 and 20. It will 70 be noted that these signals *B* and *A'* as thus arranged are in multiple, the circuits for both signals being open at circuit-controllers *m'* and *o*. The circuits of the home signal *A* and distant signal (not shown) of block *X* will be 75 now referred to. This home-signal circuit includes battery *D'*, normally-closed circuit-controller *h*', wire 15, instrument or motor of signal *A*, magnet *n*, normally open circuit-controller *m*, and wires 14 and 20. The distant signal for this block is located near the 80 entrance of block *W*, its circuit including battery *D'*, circuit-controller *h*', wire 15, wire 16, connected to 15 at 17, circuit-controller *k*, wire 18, &c., similar to circuit for distant signal *B'*. The battery *D* is connected with the 85 circuits of the home and distant signals for the block *W*, current from battery *D* passing through normally-closed circuit-controller *h*, wire 19, &c. The circuit for home signal *C* 90 is only partially shown, but it includes the wire 21, instrument or motor of signal *C*, magnet *n*², circuit-controller *m*², wire 22, wire 20, &c. The circuit of the distant signal *C'* is only partially shown, but it includes the wire 95 23, circuit-controller *o*², wires 22 and 20, &c. The circuit of the distant signal *B'* is only partially shown, but it includes the wire 21, the wire 24, connected at 25 to wire 21, circuit-controller *k*², wire 26, instrument or 100 motor of signal *B'*, circuit-controller *o*', wire 20, &c.

Circuit-controllers *h*, *k*, and *m* are controlled by magnet *a*. Circuit-controllers *h*',

k' , and m' are controlled by magnet d , and circuit-controllers h^2 , k^2 , and m^2 are controlled by magnet g .

- The operation of the system is as follows, 5 traffic moving in the direction of the arrow: A train in block W takes the current from magnet a , breaking at circuit-controller h the circuits for the home and distant signals of block W and breaking at k the circuit for the 10 distant signal of the block X , holding or putting to "danger" these signals behind the train. Circuit-controller m at the same time closes the circuit for the home signal A , putting it to "safety" in advance of the train. 15 It will be seen that the circuit for the distant signal A' cannot close at o until the circuit for the home signal has been energized and that the latter circuit, therefore, initiates the movement of the distant signal to "safety." 20 When the train enters upon subsection 2, it shunts the magnet b , thereby breaking track-circuits of magnets c and d and breaking at h' the circuit for the home signal A of block X and also the circuit for the distant signal 25 of this block located at the entrance of block W , already broken at k , thereby deenergizing magnet n and breaking at o the circuit for the distant signal A' of block Y . Signals A and A' therefore go to "danger." It also 30 breaks at k' the circuit of the distant signal A' . It also closes at m' the circuit of the home signal B , putting it to "safety" in advance of the train. The closing of this circuit at m' energizes magnet n' and closes at 35 o' the circuit of the distant signal B' , putting it to "safety" in advance of the train. When the train leaves block W , the circuit-controllers h , k , and m are restored to their normal 40 position and the circuits of the home and distant signals of block W are in a condition to be energized by a following train. The circuit of the distant signal of block X , however, located at the entrance of block W , still remains at "danger" on account of the break 45 at h' . When the train now advances upon block Y , it operates through the track-circuits of subsections 5, 6, 7, and 8 to break the circuits through circuit-controllers h^2 and k^2 and close the circuit through circuit-controller m^2 . The break at h^2 breaks the circuit for the home signal B , breaks again the circuit for the distant signal A' , already 50 broken at k' , causing signal B to go to "danger" and signal A' to remain at "danger" in the rear of the train. The break at k^2 deenergizes the circuit for the distant signal B' , putting this signal to "danger" in the rear of the train. This closing of m^2 energizes the circuit for the home signal C , putting this 55 signal to "safety" in advance of the train, and closing at o^2 by means of magnet n^2 the circuit for the distant signal C' , putting it to "safety" in advance of the train. When the train leaves block X , circuit-controllers h' , k' , 60 and m' return to their normal position, and the home and distant signals of block X are in condition to again go to "safety" before

an advancing train. Distant signal A' , however, remains at "danger" on account of the break at h^2 . Thus it will be seen that when 70 a train enters a block it puts the home and distant signals at the entrance of the block to "danger" to guard the train's rear and that at the same time it puts the home and distant signals at the entrance of the next block 75 in advance to "safety," provided, of course, this block is clear. It will also be seen that a train is guarded in the rear by the home and distant signals for the block occupied by the train, the former being located at the entrance of the block and the latter being located at the entrance of the block next in the 80 rear.

In some cases of course the normal danger-signals could be put to "safety" when the 85 train is at some other point than the entrance of a block, and this point could be located at any place in the rear of the signals that convenience might direct. Again, in some cases the distant signals could be located at points 90 other than the entrance of a block. For example, the distant signal B' might in some cases be located in the block X or in the block Y .

E and F are switches operatively connected 95 with means for controlling the electric condition of the circuit for the signals B and A' . As here shown, these means are the circuit-breakers p and p' . When the switches are closed for main-line traffic, the circuit-breakers p and p' 100 are closed, as shown, so that the signals B and A' may indicate "safety" in advance of an approaching train. When either of the switches is open, the circuits of these signals are broken and the signals cannot be put to 105 "safety."

E' and F' are switch-indicators for indicating to the switchmen the approach of a train, so that they may know whether it is safe or not to operate the switches. These indicators 110 are controlled by a circuit which is as follows: battery D^2 , circuit-controller h^2 , wire 10, wire 27, connected at 28 with wire 10, circuit-controller q , and wires 29 and 30. A magnet r , connected with wire 10 and therefore normally deenergized, controls circuit-controller q , which is normally closed, as shown, so that the circuit for the indicators is normally energized, the indicators at this time showing "safety." When a train is in the block W or 115 the block X , the current of battery D^2 finds a closed path either through the circuit-controllers k' and o or circuit-controller m' , as the case may be, and this closed path being arranged to have the proper resistance with 120 respect to the path through the indicators the circuit for the indicators will be broken at q by magnet r , and thus the indicators will show "danger."

While the embodiment of the invention as 130 herein shown and described is believed to be best for most cases, yet there are various changes in the arrangement of parts that might be made without departing from the

scope of the invention and which would secure some of the advantages thereof. For example, instead of normally-closed track-circuits, including the rails of the track, some 5 of which are so connected that when one circuit is operated another is also operated, other types of track-circuits might be employed with some advantage. In some cases track-circuits not including the rails of the tracks, 10 but including track instruments, may with some advantage be used and the track-circuits might with some advantage be not normally closed nor operatively connected together. Again, signals normally at "safety" 15 might in some cases be used with advantage. This will all be readily understood. Again, while the multiple arrangement for the electric connection of home and distant signals for a block is preferred, yet it need not in all 20 cases be employed, and the blocks need not in all cases be divided into a plurality of subsections. Various other changes which will suggest themselves to any one skilled in the art may be readily made without departing 25 from the scope or spirit of the invention.

What I claim and desire to secure by Letters Patent is embraced in the following claims:

1. In an electric signaling system for rail- 30 ways, the combination of a track divided into blocks, home and distant signals normally at "danger" for the blocks, a home signal and a distant signal being located at the entrance of each block, each home and distant signal 35 having a separate motor peculiar to itself, normally-deenergized signal-circuits for the signals and normally-closed rail-circuits controlled by a train for energizing and deenergizing the signal-circuits to operate the sig- 40 nals, the arrangement being such that a home and distant signal may be put to "safety" by a train in the rear of the signals, both of 45 said signals may be put to "danger" by a train in the block guarded by the home signal, and the distant signal may be also put to "danger" by a train in the block in advance of the block guarded by said home signal, substantially as set forth.

2. In an electric signaling system for rail- 50 ways, the combination of a block of a track divided into subsections, home and distant signals for the block normally at "danger," normally-deenergized signal-circuits for the signals, normally-closed track-circuits for the 55 subsections of the block, controlling the electric condition of the signal-circuits, said track-circuits being operated upon by a passing train for operating the home and distant signals, means controlled by a train in the rear 60 of the signals for energizing their circuits to put the signals to "safety," the arrangement being such that a train may put the home and distant signals to "safety" when in the rear thereof, may put the distant signal to "dan- 65 ger" when in advance thereof and in the rear of the home signal, and may put both signals

to "danger" when in the block guarded by the home signal, substantially as set forth.

3. In an electric signaling system for rail-ways the combination of a block of a track 70 divided into subsections, home and distant signals for the block normally at "danger," each home and distant signal having a separate motor peculiar to itself, normally-deenergized signal-circuits for the signals, nor- 75 mally-closed track-circuits for the subsections of the block controlling the electric condition of the signal-circuits, said track-circuits being operated upon by a passing train for operating the home and distant signals, means 80 controlled by a train in the rear of the signals for energizing their circuits to put the signals to "safety," said track-circuits including the rails of the track and so connected that when one of them is operated another is also operated, the arrangement being such that a train 85 may put the home and distant signals to "safety" when in the rear thereof, may put the distant signal to "danger" when in advance thereof and in the rear of the home sig- 90 nal, and may put both signals to "danger" when in the block guarded by the home sig- 95 nal, substantially as set forth.

4. In an electric signaling system for rail-ways, the combination of a track divided into 95 blocks, home and distant signals for the blocks, a home and a distant signal being located at the entrance to each block, each home and distant signal having a separate motor 100 peculiar to itself, signal-circuits for the signals, and normally-closed track-circuits controlled by a train for operating the signal-circuits to put the signals to "danger," the ar- 105 rangement being such that the home and distant signals at the entrance of a block may be put to "danger" and held there while a 110 train occupies the block immediately in advance of the signals, the distant signal being also held at "danger" while the train is in the next block in advance, substantially as set forth.

5. In an electric signaling system for rail-ways, the combination of a series of blocks di- 115 vided into subsections, normally-closed track- 120 circuits for the subsections, home and dis- 125 tant signals normally at "danger" for the blocks, a home signal and a distant signal being located at the entrance of each block, each home and distant signal having a sepa- 130 rate motor peculiar to itself, normally-deenergized signal-circuits for the signals controlled by the track-circuits, the arrangement being such that a train operates a track-circuit in the rear of a home signal and a distant signal at the entrance of a block to put the signals to "safety," and operates the track-circuits of the block immediately in advance of said signals to put the signals to "danger" and operates one or more track-circuits of the block next in advance to hold the distant sig- 135 nal at "danger," substantially as set forth.

6. In an electric signaling system for rail-

ways, the combination of a series of blocks divided into subsections, normally-closed track-circuits for the subsections, home and distant signals for the blocks, a home signal and a distant signal being located at the entrance of each block, signal-circuits for the signals controlled by the track-circuits, the arrangement being such that a train operates the track-circuits of the block immediately in advance of the home and distant signals that are at the entrance of said block to cause them to show "danger" and operates one or more track-circuits of the block next in advance to cause the said distant signal to show "danger," substantially as set forth.

7. In an electric signaling system for railways, the combination of a series of blocks, each divided into subsections, track-circuits for the subsections adapted to be operated by a train and so connected that when one is operated another is also operated, home and distant signals for the blocks, each home and distant signal having a separate motor peculiar to itself, normally at "danger," a home signal and a distant signal being located at the entrance of each block, normally-deenergized signal-circuits for the signals, controlled by the said track-circuits, the arrangement being such that a passing train may put the home and distant signals at the entrance of a block to "safety" when in the rear of said signals, may put said signals to "danger" when in the said block, and may hold the distant signal at "danger" when in the next block in advance, substantially as set forth.

8. In an electric signaling system for railways, the combination of a series of blocks divided into subsections, track-circuits for the subsections so connected that when one is operated another is also operated, home and distant signals for the blocks, a home signal and a distant signal being located at the entrance of each block, signal-circuits for the signals controlled by the track-circuits, the arrangement being such that a train operates the track-circuits of the block immediately in advance of the home and distant signals that are at the entrance of said block to cause them to show "danger" and operates one or more track-circuits of the block next in advance to cause the said distant signal to show "danger," substantially as set forth.

9. In an electric signaling system for railways, the combination of a track divided into blocks, home and distant signals normally at "danger" for the blocks, a home signal and a distant signal being located at the entrance of each block, normally-deenergized signal-circuits for the signals and means controlled by a train for energizing and deenergizing the signal-circuits to operate the signals, each home and distant signal having a separate motor peculiar to itself, the arrangement being such that a home and distant signal may be put to "safety" by a train in the rear of the signals, both of said signals may be put to "danger" by a train in the block guarded

by the home signal, and the distant signal may also be held at "danger" by a train in the block in advance of the block guarded by said home signal, the circuits for the home and distant signals at the entrance of a block being so connected that the operation of the circuit for the home signal to put it to "safety" initiates the operation of the circuit for the distant signal to put it to "safety," substantially as set forth.

10. In an electric signaling system for railways, the combination of a series of blocks divided into subsections, normally - closed track-circuits for the subsections, home and distant signals normally at "danger" for the blocks, a home signal and a distant signal being located at the entrance of each block, normally-deenergized signal-circuits for the signals controlled by the track-circuits, the arrangement being such that a train operates a track-circuit in the rear of a home signal and a distant signal at the entrance of a block to put the signals to "safety," and operates the track-circuits of the block immediately in advance of said signals to put the signals to "danger" and operates one or more track-circuits of the block next in advance to hold the distant signal at "danger," the circuits for the home and distant signals at the entrance of a block being so connected that the operation of the circuit for the home signal to put it to "safety" initiates the operation of the circuit for the distant signal to put it to "safety," substantially as set forth.

11. In an electric signaling system for railways, the combination of a series of blocks, each divided into subsections, track-circuits for the subsections adapted to be operated by a train and so connected that when one is operated another is also operated, home and distant signals for the blocks, each home and distant signal having a separate motor peculiar to itself, normally at "danger," a home signal and a distant signal being located at the entrance of each block, normally-deenergized signal-circuits for the signals, controlled by the said track-circuits, the arrangement being such that a passing train may put the home and distant signals at the entrance of a block to "safety" when in the rear of said signals, may put said signals to "danger" when in the said block, and may put the distant signal to "danger" when in the next block in advance, the circuits for the home and distant signals at the entrance of a block being so connected that the operation of the circuit for the home signal to put it to "safety" initiates the operation of the circuit for the distant signal to put it to "safety," substantially as set forth.

12. In an electric signaling system for railways, the combination of a track divided into blocks, track-circuits for the blocks, home and distant signals normally at "danger" for the blocks, a home signal and a distant signal being located at the entrance of each block, each home and distant signal having a sepa-

rate motor peculiar to itself, normally-deenergized signal-circuits for the signals controlled by the track-circuits, the arrangement being such that a train operates the signals in 5 advance to put them to "safety," the train being guarded in the rear by a home signal at "danger" and two distant signals at "danger," substantially as set forth.

13. In an electric signaling system for rail-
ways, the combination of a normally-closed
track divided into blocks, track-circuits for
the blocks, home and distant signals normally
at "danger" for the blocks, a home signal
and a distant signal being located at the en-
15 trance of each block, normally-deenergized
signal-circuits for the signals controlled by
the track-circuits, the arrangement being

such that a train operates the signals in ad-
vance to put them to "safety," the train be-
ing guarded in the rear by a home signal at 20
"danger" and two distant signals at "danger,"
the circuits for the home and distant signals
at the entrance of a block being so connected
that the operation of the circuit for the home
signal to put it to "safety" initiates the op-
eration of the circuit for the distant signal to
put it to "safety," substantially as set forth. 25

In testimony whereof I have signed my
name to this specification in the presence of
two subscribing witnesses.
